Atty.

UNITED STATES PATENT OFFICE.

LEE K. ELLIS, OF EAST LYNN, MASSACHUSETTS, ASSIGNOR TO LYNN LAST COMPANY,
OF LYNN, MASSACHUSETTS, A CORPORATION OF MASSACHUSETTS.

LAST.

1,290,141.

Specification of Letters Patent.

Patented Jan. 7, 1919.

Application filed May 14, 1918. Serial No. 235,041.

To all whom it may concern:

Be it known that I, LEE K. ELLIS, a citizen of the United States of America, and a resident of East Lynn, in the county of 5 Essex and Commonwealth of Massachusetts, have invented certain new and useful Improvements in Lasts, of which the following is a specification.

This invention relates to improvements in 10 lasts used in the manufacture of boots and shoes, and particularly to that class of lasts that are divided transversely and are adapted to be shortened to facilitate the ready removal of the shoe.

15 The removal of a turned shoe from a last of ordinary construction is made with considerable difficulty, and to remedy this defect and provide a last from which the shoe may be removed without difficulty is the object of the present invention.

20 The invention consists in certain novel features of construction and arrangement of parts which will be fully understood by reference to the description of the drawings and to the claims hereinafter given.

25 For the purpose of illustrating the invention one preferred form thereof is illustrated in the drawings, this form having been found to give satisfactory and reliable 30 results, although it is to be understood that the various instrumentalities of which the invention consists can be variously arranged and organized and the invention is not limited to the precise arrangement and organization 35 of these instrumentalities as herein shown and described, except as required by the scope of the appended claims.

Of the drawings:

40 Figure 1 represents a vertical section of a last embodying the features of the present invention.

Fig. 2 represents a similar section with the heel part moved relatively to the fore part in order to shorten the last.

45 Fig. 3 represents a horizontal sectional detail on line 3, 3, on Fig. 1.

Fig. 4 represents an end view of one of the pintles.

50 Fig. 5 represents a transverse section of a pinte on line 5, 5, on Fig. 3 and

Fig. 6 represents a plan of a pinte.

In the drawings, 10 is the fore part and 11 the heel part of a last transversely di-

vided on the inclined line 12, 13, extending downwardly from the point 12 intermediate 55 the comb 14 and heel end of the last and forwardly toward the toe end 15.

Before dividing the last on the line 12, 13, a cylindrical hole 16 is bored into the same from the bottom of the last, the axis of said 60 hole being on the line of 12, 13, so that when divided the adjacent faces of the heel and fore parts will each have therein a semi-cylindrical groove.

In the fore part 10 are mounted two 65 parallel pintles 17, 18 anchored in said fore part by means of a pin 19. Similarly mounted in the heel part 11 are two pintles 20, 21 anchored in said heel part by the pin 22. 70

Each pinte 17, 18, 20 and 21 is provided with a transverse groove 9 therein leaving a flat face at the top which facilitates the boring through said pintles of the transverse holes to receive the anchor pins 19 and 22. 75

The pintles 17, 18, 20 and 21 are all positioned in holes bored into the fore part 10 and heel part 11, and then the holes to receive the anchor pins 19 and 22 are bored 80 into the fore part and heel part and through the pintles positioned in said parts and then the anchor pins 19, 22 are inserted, thereby securely locking said pintles in position.

Each pinte 17, 18, 20 and 21 is provided with a flat sided ear 23 having an opening 85 24 therethrough to receive a rod 25, said rod extending through the openings 24 in all of the pintles and retaining the adjacent faces of the fore part and heel part in contact at all times. 90

The ears 23 of the pintles 20, 21 are respectively beneath the ears of the pintles 17, 18 and are normally held in contact therewith by the helical spring 26 surrounding the rod 25 and interposed between the upper 95 pinte 20 in the heel part 11 and the lower pinte 18 in the fore part 10.

The ears 23 of the pintles 17, 18 extend into the vertical groove in the front face of the heel part 11 and the ears 23 of the pintles 20, 21 likewise extend into the groove in the rear face of the fore part 10. 100

The openings 24 in the ears 23 are all in alinement and in the plane of the transverse division between said fore part 10 and heel 105 part 11.

In the upper end of hole 16 is placed a semi-cylindrical plug 27 and secured to the fore part 10, this plug 27 bearing against the upper end of the rod 25 thereby preventing 5 upward movement thereof.

Beneath the lower end of said rod is positioned a pin 28 driven into the fore part 10 and preventing any downward movement of said rod.

10 The spring 26 between the pintle 20 and 18 normally retains the last in extended position as shown in Fig. 1. As soon as it is desired to shorten the last the parts 10, 11 are moved relatively to each other into 15 the position shown in full lines in Fig. 2 and the last is immediately shortened in an obvious manner.

By varying the inclination of the dividing cut between the parts 10, 11, the degree 20 of shortening will be varied.

The heel part 11 is provided with the usual pin socket 29 by which the last is supported on the usual supporting pin during the lasting operation.

25 It is obvious that by this construction of last all upward movement of the heel part 11 relatively to the fore part 10 is prevented, the parts of the last being retained normally in extended position by means of the spring 30 26, and when it is desired to shorten the last while placing a shoe thereon or removing it therefrom, the fore part will be moved toward the top of the last in the direction of the arrow *a* against the tension of the 35 spring 26 which will return the parts to their normal position as soon as all outside pressure has been removed.

This makes a very simple construction of 40 last, easily manufactured, and very effective in operation.

It is believed that the operation and many advantages of a last thus constructed will be very apparent without further description.

45 Having thus described my invention I claim:

1. A transversely divided last consisting of a fore part and a heel part divided on a line inclined downwardly; a pair of pintles 50 in each part extending toward the other part; a rod extending through all of said pintles; and a spring surrounding said rod between two pintles, one of which extends from each part.

55 2. A transversely divided last consisting of a fore part and a heel part divided on a line inclined downwardly; a pair of pintles in each part extending toward the other part; a rod extending through all of said 60 pintles; and a spring surrounding said rod between the lower pintle of the fore part and the upper pintle of the heel part.

65 3. A transversely divided last consisting of a fore part and a heel part divided on a line inclined downwardly toward the toe;

a pair of pintles in each part extending toward the other part; a rod extending through all of said pintles; and a spring surrounding said rod between two pintles, one of which extends from each part. 70

4. A transversely divided last consisting of a fore part and a heel part divided on a line inclined downwardly toward the toe; a pair of pintles in each part extending toward the other part; a rod extending through all of said pintles; and a spring surrounding said rod between the lower pintle of the fore part and the upper pintle of the heel part. 75

5. A transversely divided last consisting of a fore part and a heel part divided on a line inclined downwardly; a pair of pintles in each part extending toward the other part; a rod extending through all of said pintles; a spring surrounding said rod between two pintles, one of which extends from each part; and means for preventing 80 outward movement of said pintles. 85

6. A transversely divided last consisting of a fore part and a heel part divided on a line inclined downwardly; a pair of pintles in each part extending toward the other part; a rod extending through all of said pintles; a spring surrounding said rod between two pintles, one of which extends 90 from each part; and anchors for said pintles embedded in said fore part and heel part. 95

7. A transversely divided last consisting of a fore part and a heel part divided on a line inclined downwardly; a pair of pintles in each part extending toward the other part; a rod extending through all of said pintles; a spring surrounding said rod between two pintles, one of which extends from each part; and a member in each part 100 extending through both pintles positioned therein. 105

8. A transversely divided last consisting of a fore part and a heel part divided on a line inclined downwardly; a pair of pintles in each part extending toward the other part; a rod extending through all of said pintles; a spring surrounding said rod between two pintles, one of which extends from each part; and means for preventing 110 end movement of said rod. 115

9. A transversely divided last consisting of a fore part and a heel part divided on an inclined line with their abutting faces each provided with a semi-cylindrical groove; a member secured to the heel part and extending into the groove in the fore part; a member secured to the fore part and extending into the groove in the heel part; a rod extending from one member and slidable 120 through the other; and a spring surrounding said rod between said members. 125

10. A transversely divided last consisting of a fore part and a heel part divided on an inclined line with the abutting faces each 130

provided with a semi-cylindrical groove; two members secured to each part and projecting into the groove of the other part; a rod extending through all of said members; 5 and a spring surrounding said rod between the lower member of the fore part and the upper member of the heel part.

Signed by me at Boston, Mass., this 29th day of April, 1918.

LEE K. ELLIS.
